UNITED STATES PATENT OFFICE.

RALPH M. JACKSON, OF LA HABRA, CALIFORNIA.

FUMIGATING APPLICATOR.

Application filed November 20, 1922. Serial No. 602,317.

To all whom it may concern:

Be it known that I, RALPH M. JACKSON, a citizen of the United States, residing at La Habra, in the county of Orange and State of California, have invented a new and useful Fumigating Applicator, of which the following is a specification.

My invention relates to measuring devices and gasifiers for applying liquid gases for fumigating purposes under covered trees.

Among the objects of this invention is to provide suitable means in a device of this character whereby lever means for producing pressure may be employed with a vertically disposed pump measuring means and means whereby a series of fixed measurements may be measured and discharged in intermittent expulsions from said pump means through discharge nozzle means being laterally spaced from and in approximate horizontal alignment with the lower end of said pump means and at an appreciable distance from said pump means.

Other objects may hereinafter appear.

The accompanying drawings clearly illustrate the structure.

Fig. 1 of the drawings is a side elevation of my device with portions of the structure cut away for clearness including a portion of the supply receptacle and showing in section the pump mechanism associated therewith.

Fig. 2 is an enlarged sectional detail of the vaporizing nozzle means and showing the fluid controlling means associated therewith for controlling the free flow of fluid through the nozzle.

Fig. 3 is a front end view of the supply receptacle and of the mechanism associated therewith.

Fig. 4 is a back end view of the supply receptacle and the mechanism associated therewith and illustrates in detail the measure controlling member and the association therewith of the lever actuating member.

Fig. 5 is an enlarged sectional detail of the pump plunger and pump valve mechanism with compression ring in place but with plunger packing material not shown.

In detail construction the device comprises a supply receptacle 1 for fumigating material. A pump cylinder 2 connected at its upper end through the collar 3 to the bottom of receptacle 1, and at its lower end is connected to a pump base 4 which is in turn connected to a base board 5. A pump

plunger 6 working in the cylinder 2 and provided with the compression ring 6^a is provided with a central valve mechanism comprising a ball 7 and a seat 8 situated at the upper end of plunger 6, a piston rod 9 extends downwardly through ball 7 and through the plunger 6 forming a guide therefor, screw adjusting means 10 is provided at the lower end of piston rod 9. Piston rod 9 extends upwardly from plunger 6 and through a stuffing box 11 provided at the top of receptacle 1 and is pivotally connected at its upper end to the lower end of a connecting rod 12 which is pivotally connected at its upper end to a lever actuating member 13, the same being pivotally connected to the upper end of an upright support 14 which support projects downwardly and around one side of receptacle 1 to the base 5 and is securely attached thereto at its lower end. An upright support 15 is attached at its lower end to base 5 and projects upwardly and around the side of receptacle 1 to a point above said receptacle 1 and forms a support at its upper end for one end of a handle 16 which is provided for carrying the device. Screws 17, 18, 17^a and 18^a form a tie between the supports 14, 15, 19 and 21 above and below receptacle 1. Upright support 19 is secured at its lower end to base 5 and extends upwardly to receptacle 1 and around same to a point above the receptacle forming part of a support for a measure controlling member 20 and supports one end of handle 16. Upright support 21 which also supports controlling member 20 extends downwardly from said member 20 around one side of receptacle 1 to base 5 and is secured thereto at its lower end. Fluid conducting means 22 is connected at one end to the lower end of pump cylinder 2 and projects laterally therefrom and at the other end connects with vaporizing nozzle means 23. A ball valve 24 is provided in the nozzle means 23 for controlling the free flow of fluid through the nozzle and is opened by pressure flow of fluid, a spring 25 closes the valve when pressure is off. A screw plug 26 is provided in the top of nozzle means 23 and has a guide pin extension 27 which forms a guide for spring 25. A filler port 28 having the cap 29 is provided in the top of receptacle 1. Adjusting screws 30 and 31 are provided for the measure controlling member 20. Vent line 32 which is connected at its upper end to a vent chamber 33 at the

top of receptacle 1 projects downwardly to a point in horizontal alignment with discharge line 22 and thence laterally to a point adjacent the nozzle means 23. Lever 13 is provided with a boss member 34 which is adapted to engage with the shoulder 35 of the controlling member 20. The device is operated by the handle 36. A glass tube 37 is provided for determining the quantity of liquid in the supply receptacle.

In operating the device the measurement of fluid is accomplished with a uniform stroke of the actuating lever 13, controlled by the measure controlling member 20 a full stroke accomplishing the measurement of five units, the measurement of one unit being accomplished by springing the actuating lever 13 to the right causing the boss member 34 on the side of the actuating member to engage with the shoulder 35 of the measure controlling member. For example, if a measurement of eleven units were desired the operator would raise the actuating lever until it engaged with the controlling member screw 30, the action would raise the ball valve 7 slightly, through lost motion in the valve mechanism but sufficient to permit the space in the pump cylinder below the plunger to fill, the operator would then throw the lever downwardly causing the ball valve to close and a continuation of such downward movement until the actuating lever engaged with the controlling member screw 31 would cause the expulsion from the pump of five units of fluid, a repetition of such operation would accomplish the measurement of ten units and it would then require the employment of the means provided for the measurement of one unit to accomplish the measurement of the eleven units. Other measurements of different denominations would be accomplished in the same manner using the one unit measure when the five units could not be employed.

By means of the lever 13 the fluid is forced

from the pump through the nozzle with sufficient pressure to convert the fluid into vapor. The valve 24 by checking the free flow of fluid from the line 22 provides means whereby a series of fixed measurements may be measured and discharged in intermittent expulsions from the pump means through the nozzle means.

Although the device is illustrated in the present preferred construction it is to be understood that various detail alterations in the structure within the skill of the workmen may be made without departing from the scope of the invention.

Having thus described my invention, I claim:

A fumigating applicator including a supply receptacle for fumigating fluid, base means, supporting means attached to said base means and projecting upwardly from said base means to a point above said receptacle, vertically disposed pump measuring means for measuring said fluid the measurement thereof representing a plurality of units, a horizontally disposed actuating lever for said pump means supported by said supporting means, a measure controlling member for controlling the said actuating member and for determining the unit measurement of the said measuring means, vaporizing discharge nozzle means laterally spaced from the said measuring means and fluid conducting means connecting said nozzle means with the said measuring means, fluid controlling means associated with the said nozzle means and adapted to control the free flow of fluid through the said nozzle means.

In testimony whereof I hereunto affix my signature in the presence of two witnesses.

RALPH M. JACKSON.

Witnesses:

JAMES H. WALKER,
Mrs. J. E. BROWN.

Certificate of Correction.

It is hereby certified that in Letters Patent No. 1,477,125, granted December 11, 1923, upon the application of Ralph M. Jackson, of La Habra, California, for an improvement in "Fumigating Applicators," an error appears in the printed specification requiring correction as follows: Page 2, lines 66 and 67, in claim, strike out the words "to a point above said receptacle"; and that the said Letters Patent should be read with this correction therein that the same may conform to the record of the case in the Patent Office.

Signed and sealed this 8th day of January, A. D., 1924.

[SEAL.]

KARL FENNING,
Acting Commissioner of Patents.
